(57) **CLAIM**

We claim the ornamental design for a portable electronic device displaying graphic user interface, as shown and described.

DESCRIPTION

FIG. 1 is a front view of a portable electronic device displaying graphic user interface showing our new design;

FIG. 2 is a front view of a portable electronic device displaying graphic user interface showing our new design; and,

FIG. 3 is a front view of a portable electronic device displaying graphic user interface showing our new design.

The appearance of the transitional image sequentially transitions between the images shown in FIGS. 1-3. The process or period in which one image transitions to another image forms no part of the claimed design.

The broken line showing of the mobile terminal, and the symbols, is included for the purpose of illustrating environmental structure and portions of the article, respectively, and forms no part of the claimed design.
